DESIGN FOR A COMBINED PHOTO AND MATCH BOOK COVER

Samuel Altman and Frank Silverstein,
New York, N. Y.

Application April 1, 1943, Serial No. 109,882

Term of patent 7 years

To all whom it may concern:

Be it known that we, Samuel Altman and Frank Silverstein, both citizens of the United States of America, and both residing in New York, N. Y., have invented a new, original, and ornamental Design for a Combined Photo and Match Book Cover, of which the following is a specification, reference being made to the accompanying drawing, forming a part thereof.

Fig. 1 is a front view of a combined photo and match book cover embodying our new design.

Fig. 2 is a view of the combined photo and match book cover in open position.

Fig. 3 is a side elevational view of Fig. 2.

We claim:

The ornamental design for a combined photo and match book cover, substantially as shown.

SAMUEL ALTMAN.
FRANK SILVERSTEIN.
